Notice of Allowance, U.S. Appl. No. 29/369,115, dated Mar. 17, 2011.

Primary Examiner — Thomas Johannes

(74) Attorney, Agent, or Firm — Wolf, Greenfield & Sacks, P.C.

(57) **CLAIM**

The ornamental design for a beverage cartridge, as shown and described.

DESCRIPTION

FIG. 1 is a top, front, right side perspective view of the beverage cartridge showing my new design;

FIG. 2 is a top, front, left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.
